Primary Examiner — Philip S Hyder(74) *Attorney, Agent, or Firm* — McCarter & English, LLP; James M. Smedley; Alex Korona(57) **CLAIM**

I claim the ornamental design for a compact cutter, as shown and described.

DESCRIPTION

FIG. 1 is a top, front and right-side perspective view of a compact cutter, showing the new design;

FIG. 2 is a top plan view thereof;

FIG. 3 is a bottom plan view thereof;

FIG. 4 is an inverted left side elevation view thereof;

FIG. 5 is a right-side elevation view thereof;

FIG. 6 is a front elevation view thereof;

FIG. 7 is a rear elevation view thereof; and,

FIG. 8 is a top plan view thereof; wherein the switch is in the forward position.

The shading lines shown in the drawings represent the approximate three-dimensional contour of the design, and are not intended to indicate surface decoration.

The broken line(s) shown in the drawings illustrate portions of the compact cutter that form no part of the claimed design.
